US00D894841S

(12) **United States Design Patent** (10) Patent No.: **US D894,841 S**
Mickler et al. (45) Date of Patent: **** Sep. 1, 2020**

(54) **REVERSIBLE TRAILER BLOCK TERMINAL PLATE**

(71) Applicant: **Rockwell Automation Technologies, Inc.**, Mayfield Heights, OH (US)

(72) Inventors: **Kurt R. Mickler**, Waukesha, WI (US); **Douglas R. Berger**, Milwaukee, WI (US); **Robert G. Rushmer**, Wauwatosa, WI (US); **Ganesh B. Gaikwad**, Milwaukee, WI (US)

(73) Assignee: **Rockwell Automation Technologies, Inc.**, Mayfield Heights, OH (US)

(**) Term: **15 Years**

(21) Appl. No.: **29/679,460**

(22) Filed: **Feb. 6, 2019**

(51) LOC (12) Cl. **13-03**

(52) U.S. Cl.

USPC **D13/146**

(57) **CLAIM**

The ornamental design for a reversible trailer block terminal plate, as shown and described.

DESCRIPTION

FIG. 1 illustrates a perspective view of a reversible trailer block terminal plate;

FIG. 2 illustrates a top plan view;

FIG. 3 illustrates a front view; and,

FIG. 4 illustrates a left plan view.

In this drawing, the solid lines illustrate the claimed ornamental design, whereas the broken lines illustrate environmental features that form no part of the claimed ornamental design.
